SOLVENT AND PROCESS FOR DEWAXING
MINERAL OILS

Sijbren Tijmstra, Berkeley, and Donald S. McKittrick, Oakland, Calif., assignors to Shell Development Company, San Francisco, Calif., a corporation of Delaware

No Drawing. Application July 17, 1934,
Serial No. 735,626

7 Claims. (CL 196—13)

This invention relates to a process for separating from mineral oils various waxy substances occurring therein. More particularly it pertains to a diluent for decreasing the viscosity of the oil and the solubility of the wax, whereby the wax and the oil are separated more readily than has been possible heretofore.

Mineral oils naturally contain varying amounts of waxy paraffins or petrolatum, hereinafter designated as waxes, which at normal temperatures are dissolved in the liquid hydrocarbons, but which solidify at lower temperatures. If these oils are to be used as lubricants at these low temperatures these waxy constituents tend to solidify and may cause the oil to resist flow. When the wax content is too low to impede the flow it may, nevertheless, cause cloudiness in the oil. It becomes necessary therefore, to effect the removal of these waxy constituents.

The first step in such a process is the creation of conditions under which the wax has a minimum solubility in the phase containing the remainder of the oil. This probably contains aliphatic hydrocarbons and belongs to the group of components of petroleum which are the least soluble in selective solvents. The removal of wax may be accomplished by any of the following methods.

In accordance with one method, the oil is chilled to a temperature substantially below that at which the wax solidifies and the wax may be removed from the oil by mechanical means. As an improvement in such a process, it is common to add a non-selective diluent, such as liquefied normally gaseous hydrocarbons, light napthas, etc., to the oil to reduce its viscosity and facilitate the mechanical separation.

In another method, a selective solvent is used, and the wax-free components of the oil are dissolved therein. This method necessitates the use of a solvent which is sufficiently selective to dissolve at a suitable temperature the oily components of the wax containing mixture without substantially dissolving the waxy components.

The most selective solvents, however, are not sufficiently soluble in even the non-waxy components for efficient dewaxing. To obviate the resulting difficulties, it was proposed to dilute the oil with a non-selective solvent which would dissolve the wax as well as the oil. A second solvent, often called an antisolvent, which was a poor solvent for wax, was added to the mixtures of the oil and the first non-selective solvent. This second solvent was not, however, chosen on the basis of its selective properties, but merely to counteract

the solvent effect of the first solvent when the oil was chilled to precipitate the wax.

It is an object of our invention to provide a process for the efficient dewaxing of oil. It is a further object of our invention to provide a solvent mixture which is suitable for this process. Further objects of our invention are: to provide a solvent mixture which will produce an oil which has a pour point which is near to or even substantially below the temperature at which the wax is separated; to provide a solvent mixture which will cause the paraffin wax to separate in a much purer form and in a form in which it can be more readily separated from the oil, than has been possible with the solvents now known; to provide a solvent mixture which will overcome the disadvantages of solvents heretofore known, and which can be used on all types of mineral oils by a slight variation in the properties of its constituents. Other objects of our invention will be apparent to those skilled in the art from a reading of this specification.

The method which is the subject of our invention relies primarily on the peculiar properties of mixtures of solvents, at least one of which possesses selective properties, to create a medium in which there is a large difference in solubility of the different components of oil and especially between the solubility of the solid or waxy components and the solubility of the liquid or non-waxy components.

It is well known that the presence of a selective solvent in a liquid phase containing oil components creates a medium in which there is a difference in the solubility of the various oil components. It has been found, however, that the effect of the selective solvent in creating such a difference in solubility of the various oil components depends on the concentration of the selective solvent in the liquid phase, sometimes known as the solvent rich or extract phase. In dewaxing processes this is the phase which contains primarily the non-waxy components. It is apparent that as the solubility of the wax component in this phase is made smaller the efficiency of the dewaxing process is increased.

Most of the selective solvents are very slightly soluble in the oil or in the non-waxy components of the oil at the low or moderate temperatures of the dewaxing operation and the effect of the selective solvent in creating or enhancing the difference in solubility between solid and liquid components is limited by its solubility. This limit can be increased by adding a secondary solvent which is

a good solvent for both the oil and the selective or primary solvent.

We, therefore, select a highly selective solvent as a primary solvent, and add to it (in any manner as by physically mixing together, or adding separately to the oil, etc.,) a secondary solvent, which may be known as a solubility enhancing agent, and which dissolves both the oil and the primary solvent, and use the mixture of the two solvents (in whatever manner produced) as a diluent to dissolve the liquid components of the oil, and to precipitate the wax. Under certain conditions this mixture has the further effect of reducing the viscosity of the oil to aid in the separation of the liquid and solid phases.

In our process the components precipitated are primarily waxy components, both light and heavy, having a melting point above the temperature at which the dewaxing operation is carried out. There is, however, no sharp distinction on the basis of the melting point, and a certain amount of hydrocarbons having melting points below the said operating temperature will be removed with the precipitated hydrocarbons of higher melting points. It is not, therefore, necessary to operate at a temperature which is as low as the lowest melting fraction of the wax which it is desired to remove.

In one aspect, this method, therefore, comprises the steps of mixing oil containing wax with a selective solvent mixture, and chilling to a temperature which is below the melting point of the highest melting components of the wax to be removed and separating precipitated wax at this temperature. This will result in the removal of not only those components of wax which are normally solid at the temperature at which separation occurs but also of some of those which have melting points which are below that temperature.

It is desirable, although not essential, to produce a homogeneous oil-solvent system prior to the precipitation step. To achieve this, the temperature of the system will often be initially raised somewhat above the dewaxing temperature. In this event the oil-solvent mixture must be chilled to the temperature necessary to solidify certain portions of the wax, as explained above. Some of our dewaxing mixtures may, however, be used at ordinary temperatures, and require no chilling.

The chilling, when used in this process, is not only for the purpose of merely freezing out the wax, as in the processes now practiced, but also for the purpose of increasing the selectivity of the solvent mixture which may have been added to the oil at a temperature at which it is less selective. This feature distinguishes our process from those in which the wax is caused to separate by mere chilling, and a non-selective solvent or diluent is added to reduce the viscosity of the oil and expedite the separation of the solidified wax.

After the oil-solvent system of the proper temperature has been created, the waxy constituents are separated from the liquid phase by means of any appropriate mechanical means, as filtering, settling or centrifuging. Under certain conditions the wax which is precipitated according to the procedure outlined above, either with or without chilling during precipitation, may be so soft as to make its separation difficult. It is then advantageous to chill the precipitated wax during or just prior to its final removal to harden it. Subsequently the solvent mixture is removed

from the separated phases by any means, such as distillation.

In operating according to the method of our invention it becomes possible to precipitate the wax in a form in which it can be removed more readily, particularly by filtration. When oil which does not contain a solvent or diluent is chilled to separate out the wax, the latter often assumes an amorphous form known as petro-latum. Separation by filter pressing is obviously extremely difficult. The same results may be obtained when a diluent is used which exercises no selective solvent action. When, however, the wax is precipitated from an oil in the process of our invention, the wax will generally separate out in filterable particles.

To be filterable or otherwise separable from the oil-solvent phase, these particles of wax must be of suitable size and strength and/or hardness. We have found that if in precipitating the wax a very small amount of liquid oil is separated out from the oil with the wax crystals, clusters of crystals will be formed and the separation of the wax from the main body of the oil is facilitated. The amount of oil necessary for this purpose depends on the size of the wax crystals. In processes in which the crystals are extremely small and the wax content of the oil is high, as much as 1.0% of the main body of the oil may be desirable. When the crystals are larger in size or smaller in amount, lesser amounts of oil are desirable, and it is frequently practical to permit no oil to be separated out. If more than such a small quantity of oil is lost to the wax, the yield of the wax-free oil will be decreased and the precipitated wax becomes difficult to separate. It will, therefore, often be desirable to precipitate a small amount of oil with the wax, but it is then necessary to control carefully the amount of oil which is to be carried away with the wax.

A convenient method of controlling this amount of oil is to control the quantity of the solubility enhancing agent in the solvent mixture. The necessary dilution ratio, i. e., ratio of the combined solvent mixture to the oil, is generally determined by the viscosity of the oil and the solvent mixture and by the selectivity of the solvent mixture, and is made as low as possible with a view of conserving the solvent. For this given dilution ratio, the greater the concentration of the selective solvent in the oil, the more complete will be the precipitation of wax. As was pointed out above, since pure selective solvent is not sufficiently soluble in the oil, a solubility enhancing agent is added to achieve a homogeneous liquid phase. If more of this agent than is required for homogeneity is added, this condition will still be retained. In this case the concentration of the selective solvent in the liquid phase for the given dilution ratio is not, however, at its maximum, although the extraction can be conducted under these conditions. It is desirable, for the purpose of increasing the selective solvent concentration, to use only that quantity of solubility enhancing agent as is required to insure the desired degree of solubility. If the minimum amount of solubility enhancing agent for complete solubility is used, substantially no oil will separate from the oil solvent mixture when the oil-solvent mixture is chilled to precipitate wax. A good yield is produced and, under many conditions, this is the optimum quantity of solubility enhancing agent. But, as was pointed out above, it may often be difficult

to separate the wax from the oil-solvent phase. Under these conditions it is desirable to separate some oil with the wax. This may be accomplished by using less of the solubility enhancing agent. A very small quantity of oil is then lost, but the separation of the wax is made easier. This condition sometimes represents the optimum amount of solubility enhancing agent. Beyond this point a further reduction in the quantity of the solubility enhancing agent will be undesirable because of decreased yield and increased filtering difficulties.

When using the new solvent mixtures of our invention, the dilution ratio, mentioned above, may be much lower than the dilution ratio used with the known solvent mixtures. For example, excellent results have been obtained when using a dilution ratio of 2:1, and even lower ratios may at times, be suitable. With the solvents and/or solvent mixtures of the prior art much greater ratios are necessary.

As used in the claims, the term "sufficient to prevent the separation of free oil", as applied to the quantity of solubility enhancing agent, means the amount necessary to permit no more oil to be carried away with the wax than is necessary to form a readily separable wax. In situations in which no oil is needed to produce a readily separable wax, all oil not retained by the solvent is regarded as "free oil."

In another aspect, therefore, our invention comprises the steps of mixing oil containing wax with a primary selective solvent and precipitating the wax at a desired temperature in the presence of a controlled quantity of a solubility enhancing agent so as to prevent more than certain small desired amounts of oil from separating from the solvent phase.

Another advantage of our process and solvent mixtures is that it becomes possible to obtain a pour point which is near to or often, substantially below the temperature to which the oil-solvent mixture is chilled. This makes it possible to operate at substantially higher temperatures than heretofore. It is to be understood, however, that our invention is not limited to operating at any particular temperature, inasmuch as the advantages of this process and of our new solvent compositions will be realized although the extraction is practiced according to the number of alternate procedures coming within the scope and spirit of our invention. In all of these, the wax separates as a result of the action of the selective solvent or solvents and not of simple freezing out.

Selective solvent mixtures suitable for a dewaxing process of the type described must have a sufficiently high solubility for the liquid constituents of the oil at the temperatures at which the wax is separated therefrom to keep substantially all of these liquid constituents in solution. As pointed out above, since selective solvents usually possess either a low solubility for petroleum oils at the low temperatures which obtain during separation, or a low selectivity for liquid oil components at normal room temperatures, it is usually necessary to blend them with a secondary solvent, which may be known as a solubility enhancing agent, and which in combination with the primary solvent produces a solvent mixture of suitable selectivity for oil components at dewaxing temperatures.

Of the many substances which can be used as secondary solvents those should, preferably, be selected which have a low solubility for paraffin

wax. While a degree of selectivity of the secondary solvent is not an absolute requirement, it will be found that a greater efficiency often results in cases of using for that purpose a fairly selective solvent. For example, butyl alcohol usually gives better results than hexane or benzol.

We have found that there exists two broad groups of substances, the first of which includes substances which are good selective solvents but in which the oil is generally not sufficiently soluble. The second group includes substances which are primarily good solvents for both the primary solvent and for the oil, but which may possess selective properties of a certain degree.

The first group includes the following substances:

I. Non-hydrocarbon derivatives of the following cyclic compounds: benzene rings (C_6H_6), heterocyclic rings (of the type C_4H_4O , C_4H_4S or C_4H_4NH), pyridine rings (C_5H_5N) or six-membered rings with two atoms of N, or O, or N plus O, or N plus S, each with at least one of the following substituents: $—OH$, $—CO$, $—CHO$, $—COOH$, $—R$, $—COOR$ (where R stands for an alkyl or aryl radical), $—Cl$, $—Br$, $—I$, $—NO_2$, $—NH_2$, $—ONO$, $—SH$, $—CS$, $—CONH_2$, $—SCN$, $—CN$. Also condensed ring systems containing one or more of the above ring types and certain products of industrial processes having complex compositions.

Examples.—Benzene nitrile, benzene nitrite, nitrobenzene, nitrotoluene, aniline, diphenyl amine, phenol, chlorophenol, cresol, cresylic acid, "acid oils" described hereinbelow, quinoline, pyridine, furfural, thiophene, thiophenol, lutidine, picoline, thionaphthol,

II. Lower aliphatic acids, hydroxy or keto aliphatic acids, anhydrides of aliphatic acids, and sulphur analogues of the above acids, all containing not more than four carbon atoms in the molecule.

Examples.—Diacetone alcohol, acetic acid, butyric acid, lactic acid, acetic anhydride, thioacetic acid.

III. Aliphatic alcohols, aldehydes, ketones, ethers, acids, acid anhydrides, hydroxy or keto acids, and sulfur analogues of the above oxygenated aliphatic compounds, all containing not more than sixteen carbon atoms in the molecule and containing at least one substituent from the group: $—Cl$, $—Br$, $—I$, $—CN$, $—SH$, $—CS$, $—CONH_2$, $—SCN$, $—NH_2$.

Examples.—Chlorex ($\beta\beta'$ dichloroethyl ether), dichlorbutyl ether, dibromethyl ether, chloracetic acid, ethanol amine, triethanol amine, lactic acid,

IV. Relatively unreactive liquid inorganic compounds of S, Se, Te, Sn, Sb, as, for example, SO_2 , $SnCl_4$.

The "acid oil" contained in the above list may be prepared as follows: petroleum oil, preferably cracked distillate oil, is treated with a concentrated sulfuric acid, and the sludge is removed from the mixture. The oil is then neutralized with caustic soda and the second sludge, or spent alkali, separated from the oil. Upon acidification of this second sludge either with an acid or with the acid sludge, an oil known as "acid oil" is produced. This oil apparently contains hydroxy-aromatics and possesses selective solvent action. This property can be modified by the presence of solubility enhancing agents, such as an alcohol, to produce a selective solvent mixture which is useful in our dewaxing process.

The second group, (which contains compounds suitable for use as the secondary solvent) includes:

- I. Aliphatic alcohols, aldehydes, acids, ethers, 5 methyl ethyl or higher symmetrical or mixed ketones, and sulphur analogues of the above oxygenated aliphatic compounds, all containing not more than twelve carbon atoms in the molecule.

Examples.—Primary butyl alcohol, secondary 10 butyl alcohol, isopropyl alcohol, propylaldehyde, diethyl acetone, diethyl ether, diethyl thioether.

II. Carbon bisulfide, aliphatic amines, esters of lower fatty acids and lower alcohols containing more than four and not more than twelve carbon 15 atoms in the molecule, branched chain and cyclic aliphatic hydrocarbons (containing not more than twelve carbon atoms in the molecule), polycyclic (and particularly bicyclic) aromatic hydrocarbons, such as naphthalene and its homologues, 20 preferably dissolved in benzol or its homologues or equivalents.

Although the solvents of each of the two broad groups set forth possess the properties of their respective group, we have found that certain of 25 these substances possess these properties to an appreciably greater degree, and form distinct subgroups. Furfural, Chlorex, quinoline, nitromethane and nitrobenzene constitute the subgroup of the first group; and the following substances 30 constitute the corresponding subgroup of the second group: butyl, amyl and hexyl alcohols (secondary, tertiary, normal or iso-); ethyl, propyl, isopropyl, butyl, and isobutyl ethers; carbon disulfide; aliphatic amines; and isopentane.

35 With regard to the relative efficiency of the alcohols, better results are usually obtained with secondary than with primary, and better results with tertiary than with secondary alcohols. The alcohols of low molecular weight are not very 40 soluble in mineral oils, so that when operating at low temperatures it is preferable to use amyl and/or even hexyl or higher alcohols.

Mixtures of two or more different primary and 45 secondary solvents can be used in our solvent mixture. When used in a process in which it is desired or necessary to separate the primary solvent from the solubility enhancing agent, it becomes desirable to choose a pair of substances having substantially different boiling ranges. 50 This is, however, not necessary in certain other processes in which our solvent mixture can be used.

Pairs of substances which we have found to be especially useful, and which constitute a preferred embodiment of our invention are: (1) furfural and secondary butyl alcohol, (2) furfural and trimethyl carbinol, (3) furfural and methyl normal propyl carbinol, (4) furfural and dimethyl ethyl carbinol, (5) furfural and methyl 55 normal butyl carbinol, (6) furfural and dimethyl normal propyl carbinol, (7) Chlorex and secondary butyl alcohol, (8) Chlorex and trimethyl carbinol, (9) Chlorex and methyl normal propyl carbinol, (10) Chlorex and dimethyl ethyl carbinol, (11) Chlorex and methyl normal butyl carbinol, (12) Chlorex and dimethyl normal propyl carbinol, (13) Chlorex and isopentane, (14) nitrobenzene and secondary butyl alcohol, (15) nitrobenzene and methyl normal propyl carbinol, (16) 60 nitromethane and secondary butyl alcohol, (17) nitromethane and methyl normal propyl carbinol, (18) furfural and ethyl ether, (19) furfural and isopropyl ether, (20) furfural and isobutyl ether, (21) Chlorex and ethyl ether, (22) Chlorex and 65 isopropyl ether, (23) Chlorex and isobutyl ether,

(24) quinoline and secondary butyl alcohol, (25) quinoline and trimethyl carbinol, (26) quinoline and methyl normal propyl carbinol, (27) quinoline and dimethyl ethyl carbinol.

To illustrate the improved results obtained with 5 our new solvent mixtures, the following examples are set forth:

EXAMPLE I

To compare the efficiencies of one of our new 10 solvent mixtures and the acetone-benzene mixture, Kettleman residue from which the asphalt had been precipitated with H_2SO_4 and having a pour point of $80^{\circ} F.$ was diluted with eight times its volume of a solvent mixture. In four of these 15 tests one of our new mixtures was used, and in the fifth the known acetone-benzol mixture was used. The oil-solvent mixture was chilled and filtered at the reduced temperature. Results are 20 shown on Table I.

Table I

Exp. No.	Diluent		Temp. of filtration	Final pour point of oil	25
	Select solvent	Sol. enhancing agent			
1.....	Furfural 50%.....	S-butyl alcohol 50%.....	70	50	
2.....	.....do.....	.....do.....	35	30	
3.....	.....do.....	.....do.....	0	-10	
4.....	Acetone 35%.....	Benzol 65%.....	0	20	30

These results indicate that our solvent mixture will produce an oil having a pour point which is substantially below the temperature to which the oil-solvent mixture is chilled. They 35 also demonstrate the increased efficiency of our solvent mixture as compared with a solvent mixture of acetone and benzol. It is apparent that our solvent mixture makes it possible to operate at substantially higher temperatures than heretofore if an oil of the same pour point is desired. 40 On the other hand, if the same temperature is used, an oil with a lower pour point is produced.

EXAMPLE II

To compare the efficiencies of our various new 45 solvent mixtures and the acetone-benzol mixture, propane-deasphaltized Ventura residue having a pour point of $80^{\circ} F.$ was diluted with several solvent mixtures, chilled, and filtered. 50 The results are shown in Table II.

Table II

Exp. No.	Sel. solvent	Sol. enhancing agent	Ratio of oil to diluent	Temp. of filtration	Final pour point of oil	55
1.....	Furfural 25%.....	S-butyl alcohol 75%.....	1:4	32	25	
2.....	Furfural 20%.....	Methyl normal propyl carbinol 71%.....	1:2	.....	15	60
3.....	Furfural 18%.....	S-butyl alcohol 92%.....	1:2	.....	25	
4.....	Acetone 35%.....	Benzol 65%.....	1:4	.....	40	

A comparison of the results with experiments 65 using benzol-acetone, shows that appreciably lower pour points were obtained with the furfural-alcohol mixtures, and that efficient dewaxing is possible with our furfural-alcohol mixtures at considerably lower dilution ratios.

70 These examples are recited solely for the purpose of illustrating the efficiency of our new solvents, and not by way of limitation. Thus, the oil-solvent ratio may be varied within wide limits, according to the extent to which the mixture is 75

soluble in the oil to be dewaxed, the yield of oil desired, etc. The only requirement is that the solubility enhancing agent be present in such a quantity that when the oil-solvent mixture is chilled to precipitate the wax, the oil will remain dissolved in the solvent mixture to such a degree that free oil will be substantially prevented from being carried away with the wax. The dewaxing may be conducted either as a continuous or a batch process. It is obvious, also, that the ratio of the selective solvent to the solubility enhancing agent will vary with the solubility of the particular oil in the particular selective solvent used, and may be readily determined in any particular instance by those skilled in the art after a reading of this specification. By the term "effective quantity" as used in the claims, we mean a quantity of solvent mixture which will maintain sufficient oil in solution to produce its substantial separation from the wax which is precipitated, and which will produce an oil-solvent mixture of the desired viscosity.

Certain solvents disclosed herein and dewaxing processes involving the use thereof are claimed 25 in divisional applications.

We claim as our invention:

1. A selective solvent dewaxing mixture for petroleum oil comprising furfural and a secondary or tertiary alcohol containing more than 30 three and less than seven carbon atoms, said alcohol being present in an amount sufficient to prevent the separation of free oil from an oil-solvent mixture formed by adding an effective quantity of said dewaxing mixture to said petroleum oil when said oil-solvent mixture is chilled to a temperature at which the wax is precipitated therefrom.

2. A selective solvent dewaxing mixture for

petroleum oil comprising furfural and secondary butyl alcohol, said alcohol being present in an amount sufficient to prevent the separation of free oil from an oil-solvent mixture formed by adding an effective quantity of said dewaxing 5 mixture to said petroleum oil when said oil-solvent mixture is chilled to a temperature at which the wax is precipitated therefrom.

3. A selective solvent dewaxing mixture consisting of between 15% and 30% furfural and between 85% and 70% secondary or tertiary butyl alcohol. 10

4. A selective solvent dewaxing mixture consisting of between 20% and 35% furfural and between 80% and 65% secondary or tertiary amyl 15 alcohol.

5. The process of dewaxing mineral lubricating oils which comprises mixing said oil with furfural and a butyl alcohol of the group: secondary and tertiary butyl alcohol, chilling said mixture to 20 precipitate wax, and removing the precipitated wax from the oil-solvent mixture.

6. The process of claim 5 wherein the solvents used are taken in such proportions and quantity as to cause the cold test of the dewaxed oil to be 25 not above the temperature at which the wax is separated from the oil-solvent mixture.

7. The process of dewaxing mineral lubricating oils which comprises mixing said oil with at least one part of a solvent mixture consisting of between 15% and 30% furfural and between 85% and 70% secondary or tertiary butyl alcohol; chilling the mixture to precipitate wax; and removing the precipitated wax from the oil solvent 30 mixture. 35

SIJBREN TIJMSTRA.
